UNITED STATES PATENT OFFICE

IRA A. WEAVER, OF SPRINGFIELD, ILLINOIS, ASSIGNOR TO WEAVER MANUFACTURING COMPANY, OF SPRINGFIELD, ILLINOIS, A CORPORATION OF ILLINOIS

JACK

Application filed May 11, 1929. Serial No. 362,169.

My invention pertains to improvements in lifting jacks, and concerns more particularly those of the truck type, one of the leading aims and prime purposes of the new construction being the employment of the cylinder, in which the power piston or plunger slides for operating the jack, as the main frame of the appliance, thereby effecting simplicity in structure, operating strength 10 and economy in manufacture.

This and other features of novelty and advantage, both structural and functional, are incorporated in many of the mechanical elements of the jack and in their cooperation 15 with one another.

A salient characteristic of the new appliance is the provision of a jack of this kind plain in structure, with adequate strength to perform its work and which may be easily 20 operated and controlled.

To enable those acquainted with this art to understand the invention fully, in the accompanying drawings, forming a part of this specification, and to which reference should 25 be had, a present desirable and preferred embodiment of the invention has been illustrated in detail, like reference characters designating the same parts being used throughout the several views.

30 In these drawings:

Figure 1 is a side elevation of the improved truck jack showing the lifting saddle in its lowermost position;

Figure 2 is a plan view of the jack;

35 Figure 3 is a substantially-central, vertical, longitudinal section through the jack depicting the lifting saddle or seat in dotted lines in its uppermost position;

Figure 4 is a fragmentary, horizontal section on line 4-4 of Figure 3 on an enlarged scale;

Figure 5 is an enlarged vertical section of a portion only of the structure, as is shown in Figure 3;

45 Figure 6 is a partial elevation and partial section of the release valve and its operating mechanism on an enlarged scale on line 6-6 of Figure 4; and

50 Figure 7 is a cross-section on line 7-7 of Figure 5.

By reference to these drawings, it will be perceived that the jack comprises a main, longitudinal, horizontal, tubular member or cylinder 11 which, near one end, has welded thereto a pair of oppositely extended bearings or supports 12, 12 accommodating a shaft 13 on which a pair of carrying-wheels 14, 14 are revolvably mounted.

Adjacent to the other end of this main supporting member 11, a pair of outstanding brackets 15, 15 are welded to its outer face, and each accommodates a suitably-supported caster-wheel 16, whereby the frame of the truck jack is supported by the four wheels and may be readily shifted to any desired position by reason of the readily controlled action of the caster-wheels.

Along its top, near one end, the tubular member or cylinder is lengthwise slotted at 17, and adjacent to one end of such opening, an upstanding, bearing bracket or support 18 is welded for the accommodation of a fulcrum-pin 19 of a bell-crank lever 21, which, in its lowermost position, as shown in full lines in Figure 3, is largely accommodated inside of the cylinder 11.

At its free end, lever 21 has a bracket or support 22 fulcrumed thereon at 23, such part 22 having a circular, top, plate portion 24 on which the load saddle or seat 25, with its upstanding projections 26, 26, is revolvable, a depending, marginal flange 27 of such element being spun around the underside of the periphery of the bearing 24, whereby the member 25 may be readily turned on its support, and, since it is not perforated, and, due to its specified connection with the member 24, this bearing is fully protected from dirt and water and it also assists preventing foreign matter from reaching the bearings of the rockingly connected elements beneath it.

In order to maintain the horizontality of the seat or saddle 25 in all of its various positions, the part 22 is connected to the stationary support 18 by a pair of links 28, 28 positioned on opposite sides of the bell-crank lever 21.

To assist in the descent of such lever and its load-saddle, when there is no weight im-

posed on the latter, a coiled, contractile spring 29 is connected at one end to the member 22 and at its other end to a suitable lug 31 on the inside of the lower portion of the cylinder 11 beneath the bell-crank lever.

The end of the shorter arm of the bell-crank lever is equipped with an anti-friction roller 32 which bears on and cooperates with one end of the plane face of a plunger 33 fitting and slidable in the cylinder 11 and supplied with an appropriate leather or other packing 34 to effect a snug sliding fit with the inner surface of the cylinder.

From the foregoing, it will be clear that, when this plunger or piston is forced to the right, as the parts are viewed in Fig. 3, the bell-crank lever will be rocked upwardly to carry its saddle and the load in the same direction, and, when such plunger is permitted to travel to the left, the load-saddle and lever can descend.

An end casting 35 of irregular shape, as shown in Figure 5, is screwed into the opposite end of the cylinder 11 and its hub 36 supports an internal, smaller pump-cylinder 37, which at its inner end carries a stationary valve casting 38 supplied with a leather or other appropriate packing 39 tightly fitting against the inner surface of the cylinder 11 and constituting a stationary wall dividing the cylinder into power and reservoir portions 52 and 51, respectively.

As is clearly shown in such Figure 5, the element 38 has a spring-pressed ball-valve controlled conduit 41 connecting the space or reservoir between the cylinders 37 and 11 and the inside of the cylinder 37, another spring-pressed ball-valve controlled passage 42 connecting the interior of the cylinder 37 with the inside of the cylinder 11 to the right of the member 38.

A pump plunger 43, fitted with a suitable packing 44, is slidable inside of the cylinder 37 and extends out one end thereof through a stuffing box 44', the exposed or protruding end of the plunger being connected by a link 45 to a short extension 46 forming a part of a hollow, operating handle 47 fulcrumed on the exposed portion of the casting 35 on a suitable pin 48, such handle desirably being fitted with a top cross-piece 49 by which it may be readily grasped for actuation.

Assuming that the oil-reservoir 51 between the cylinders 37 and 11 is supplied with an appropriate quantity of oil, it will be clear that every time the handle 47-49 is rocked upwardly, causing the travel of the piston or plunger 43 to the left, oil will be sucked into the cylinder 37 through the valve-controlled passage 41, and that, when the handle is subsequently rocked downwardly, forcing the piston or plunger 43 to the right, the oil in the cylinder 37 will be expelled through the valve-governed passage 42 into the power portion 52 of the cylinder, causing the travel

of the piston or plunger 33 to the right and effecting a corresponding rocking of the bell-crank lever and the lifting of the saddle and its load.

Repetition of these movements will produce progressive or step-by-step elevation of the load.

Obviously, in order to permit descent of the saddle and the weight imposed thereon, it is necessary to provide means to allow the oil in the power-cylinder 52 to escape back into the reservoir 51, and the size of such conduit will, of course, control the speed of downward movement.

To this end, the passage 42, to the right of, its ball check-valve, is connected to an angular conduit 53, extending to the other side of the member 38, at which place it has a suitable valve-seat controlled by a conical valve 54, the stem of which projects through appropriate stuffing-boxes 56 in the reservoir piston, described hereinafter, and 57 in the end casting 35.

A spring 58 surrounds the external part of such valve-stem and bears at one end against the element 35 and at its other end against an adjustable, enlarged head 59 on the stem, the end of such head cooperating with a cam 61 appropriately mounted in a bearing 62 forming part of the casting 35 and supplied with an operating handle 63 by which it may be readily turned.

When the circular portion of the cam 61 bears on the head 59, as shown in Figures 4 and 6, valve 54 closes the passage 53, but, when the handle 63 is turned to allow the flat side of the cam to come into register with the head 59, the spring 58 expands somewhat and opens the valve 54, thus establishing direct communication between the power-cylinder 52 and the oil-reservoir 51, permitting the oil in the former to flow at a definite, slow speed into the latter, thus allowing the bell-crank lever and its saddle and load to descend at a predetermined rate.

It is desirable to provide means to permit a relatively quick, but not necessarily powerful, initial lift of the saddle to the load, after which, they may be elevated together more slowly by the intermittent pump action already presented, and, for the purpose of accomplishing this rapid preliminary lifting, the following specified cooperating instrumentalities have been provided.

An annular or centrally-apertured piston 64 in the reservoir 51 has a hub 65 slidable on the exterior surface of the pump-cylinder 37 and it also is fitted with a double leather or other suitable packing 66 which maintains a fluid-tight relation with the inner surface of the cylinder 11 and the outer surface of the pump-cylinder 37.

A coiled spring 67 encircles the pump-cylinder 37, bearing at one end against the division wall or valve member 38 and pressing at

its other end against the piston 64, tending to shift the latter to the left as the parts are viewed in the drawings.

Piston 64 has an operating rod 68 fixed thereto at 69 (see Fig. 4), the rod extending through a stuffing-box 71 in the closure member 35, its end cooperating with an arm 72 fixed on a rock-shaft 73 mounted in the casting 35 and supplied with a foot-piece or pedal 74, the depression of which rocks the shaft 73 and arm 72, causing the rod 68 and its associated reservoir-piston 64 to travel to the right.

Such movement of the piston expels oil from the reservoir 51 through the passages 41 and 42 into the power-cylinder 52 pushing the piston 33 to the right and rapidly rocking the bell-crank lever and its saddle up to the load.

As soon as the seat or saddle engages or almost touches the load, there is no further depression of the pedal, and, by the rocking of the handle 47—49, the load may be lifted step by step, the oil for this purpose being taken from that portion of the reservoir 51 between the member 38 and the reservoir-piston 64.

Stated somewhat differently, the quick, first-stage raising of the seat or saddle is brought about by reducing the size of the oil-reservoir and the expulsion of a portion of its contents into the power-cylinder.

As soon as the foot is released from the pedal 74, the expansion of the previously-contracted spring 67 pushes the reservoir-piston 64 to the left to its limit of movement, and, to facilitate this action, the piston 64 is provided with a passage 75 through it which is controlled by a leaf-spring valve 76 secured against the right-hand face of the piston by a screw 77.

When the piston 64 moves to the right, such valve 76 automatically closes the passage 75, whereby the piston may expel oil ahead of it, but, when the piston moves to the left under the action of its spring 67, the valve 76 opens of itself to permit the oil to flow through the port 75.

In order to make certain that the valve 76 will be open when the piston is at the extreme of its left hand movement, so that the oil on both sides of the piston is available to the pump, a stationary rod 78 is mounted on the member 36 and projects through the port 75 sufficiently to hold the spring valve open as is clearly illustrated in Figure 5.

Some small quantity of oil, during the operation of the jack, may escape or leak past the plunger 33, and, to restore such oil to the reservoir, a shallow dam 79 is provided across the bottom of the inside of the cylinder 11 in advance of the plunger 33 the space to the left of such shallow wall being connected to that portion of the reservoir to the left of the reservoir-piston 64 by a pipe 81, whereby,

when the piston 64 is moved to the right, or even during the normal operation of the pump, the descent of the liquid in the reservoir will create sufficient suction to draw off the small quantity of accumulated oil by the dam 79 and to deliver it back into the reservoir through the specified pipe.

From the foregoing, it will be apparent that the saddle may be quickly elevated to the load by foot actuation of the relatively-short pedal 74, and that, thereafter, by the upward and downward hand rocking of the comparatively-long handle 47—49, the load may be raised intermittently or step-by-step, its descent when desired, being permitted by hand or foot turning of the handle 63 to open the discharge-valve 54, thus allowing the oil to return from the power-cylinder into the reservoir at a predetermined, slow, regulated speed.

Those trained in this art will readily understand that this invention is not limited or restricted to the precise and exact details of structure presented and that many minor mechanical changes may be incorporated in the appliance without departure from the heart or essence of the invention, as defined by the appended claims, and without the loss of any of its material benefits or advantages.

From what precedes, it will be clear that since the power-cylinder, its valves, its plunger and the operating means therefor, and the reservoir piston are all mounted on a single casting screwed into the end of the main frame cylinder, these several elements may be demounted from the structure as a unit for repairs or replacement of worn parts by merely unscrewing the part 35 from the cylinder, which demounting operation may be facilitated by turning or rotating the handle 47 and its cross-bar 49 as a means for bringing about the separation of the members.

I claim:

1. In a lifting-jack, the combination of load-engaging means, a power-cylinder, a piston slideable in said cylinder, means operatively connecting said piston and load-engaging means, a liquid-reservoir, a pump including a cylinder and piston to force liquid from said reservoir into said cylinder to slide said piston to raise said load-engaging means, means to permit return of the said liquid in said power-cylinder into said reservoir to allow movement of said piston to permit the descent of said load-engaging means, and means to reduce the size of said reservoir and thereby force liquid therefrom into said power-cylinder to obtain a quick initial ascent of said load-engaging means.

2. In a lifting-jack, the combination of load-engaging means, a power-cylinder, a piston slideable in said cylinder, means operatively connecting said piston and load-engaging means, a liquid reservoir, a pump in-

- cluding a cylinder and piston to force liquid intermittently from said reservoir into said power-cylinder to slide said piston to raise said load-engaging means, means to permit return of the liquid in said power-cylinder into said reservoir to allow movement of said piston to permit the descent of said load-engaging means, and means to steadily reduce the size of said reservoir and thereby force liquid therefrom into said power-cylinder to obtain a quick initial ascent of said load-engaging means.
3. In a lifting-jack, the combination of load-engaging means, a power-cylinder, a piston slidable in said cylinder, means operatively connecting said piston and load-engaging means, a liquid reservoir, a hand-operated pump to force liquid intermittently from said reservoir into said cylinder to slide said piston step-by-step to raise said load-engaging means correspondingly, means to permit the return of the liquid in said power-cylinder into said reservoir to allow movement of said piston to permit the descent of said load-engaging means, and foot-operated means to steadily reduce the size of said reservoir and thereby force liquid therefrom into said power-cylinder to obtain a quick initial ascent of said load-engaging means.
4. In a lifting-jack, the combination of load-engaging means, a power-cylinder, a power-piston slidable in said cylinder, means operatively connecting said piston and load-engaging means, a pump-cylinder connected to said power-cylinder, a liquid reservoir-cylinder connected to said pump-cylinder, a hand-operated plunger slidable in said pump-cylinder to draw liquid from said reservoir into said pump-cylinder and to force it therefrom into said power-cylinder to operate said power-piston step-by-step to raise said load-engaging means correspondingly, means to permit return of the liquid from said power-cylinder into said reservoir to allow movement of said power-piston to permit the descent of said load-engaging means, a foot-operated piston slidable in said reservoir-cylinder to force liquid therefrom steadily into said power-cylinder to obtain a quick initial ascent of said load-engaging means.
5. In a lifting-jack, the combination of load-engaging means, a power-cylinder, a power-piston reciprocatory in said cylinder, means operatively connecting said power-piston and load-engaging means, a liquid reservoir-cylinder, a pump connected to said reservoir and to said power-cylinder and adapted to force liquid from the former into the latter to operate said power-piston to raise said load-engaging means, means to permit return of liquid from said power-cylinder into said reservoir-cylinder to allow descent of said load-engaging means, a ported piston slidable in said reservoir-cylinder to force liquid therefrom into said power-cylinder to obtain a quick initial lift of said load-engaging means, means to operate said reservoir-piston, a valve controlling said reservoir-piston port to close it automatically when the piston is moved in the direction to feed liquid into said power-cylinder and to open it automatically when it travels in the opposite direction.
6. In a lifting-jack, the combination of load-engaging means, a power-cylinder, a power-piston reciprocatory in said cylinder, means operatively connecting said power-piston and load-engaging means, a liquid-reservoir cylinder, a pump connected to said reservoir and to said power-cylinder and adapted to force liquid from the former into the latter to operate said power-piston to raise said load-engaging means, means to permit return of liquid from said power-cylinder into said reservoir-cylinder to allow descent of said load-engaging means, a ported piston slidable in said reservoir-cylinder to force liquid therefrom into said power-cylinder to obtain a quick initial lift of said load-engaging means, means to operate said reservoir-piston, a valve controlling said reservoir-piston port to close it automatically when the piston is moved in the direction to feed liquid into said power-cylinder and to open it automatically when it travels in the opposite direction, and means to maintain said valve open when said reservoir-piston is at substantially one end of its stroke.
7. In a lifting-jack, the combination of a tubular-member, carrying-wheels for said member, a load-engaging member, a longitudinal portion of said tubular member constituting a power-cylinder, a power-piston of substantially the same diameter as the interior of and slidable in said power-cylinder, means operatively connecting said power-piston and said load-engaging means, another longitudinal portion of said tubular-member constituting a liquid-reservoir, a smaller pump-cylinder in said reservoir-cylinder connected to the latter and to said power-cylinder, a pump-plunger reciprocatory in said pump-cylinder and adapted to force liquid from said reservoir into said power-cylinder to operate said power-piston and load-engaging means, means to permit return of liquid from the power-cylinder into said reservoir-cylinder to allow descent of said load-engaging means, a reservoir-piston surrounding and slidable on said pump-cylinder and adapted to force liquid from said reservoir into said power-cylinder to obtain a quick initial lift of said load-engaging means, and means to operate said reservoir-piston.
8. In a lifting-jack, the combination of a tubular-member, carrying-wheels for said member, a load-engaging member, a longitudinal portion of said tubular-member constituting a power-cylinder, a power-piston of substantially the same diameter as the interior of and slidable in said power-cylinder, means operatively connecting said power-piston and said load-engaging means, another longitudinal portion of said tubular-member constituting a liquid-reservoir, a smaller pump-cylinder in said reservoir-cylinder connected to the latter and to said power-cylinder, a pump-plunger reciprocatory in said pump-cylinder and adapted to force liquid from said reservoir into said power-cylinder to obtain a quick initial lift of said load-engaging means, and means to operate said reservoir-piston.

substantially the same diameter as the interior of and slideable in said power-cylinder, means operatively connecting said power-piston and said load-engaging means, another longitudinal portion of said tubular-member constituting a liquid-reservoir, a smaller pump-cylinder in said reservoir-cylinder connected to the latter and to said power-cylinder, a hand-operated pump-plunger 5 reciprocatory in said pump-cylinder and adapted to force liquid from said reservoir into said power-cylinder to operate said power-piston and load-engaging means, means to permit return of liquid from the 10 power-cylinder into said reservoir-cylinder to allow descent of said load-engaging means, a reservoir-piston surrounding and slideable on said pump-cylinder and adapted to force liquid from said reservoir into said power-cylinder to obtain a quick initial lift 15 of said load-saddle.

11. In a lifting-jack, the combination of a main-cylinder, a movably-mounted load-saddle, a piston of substantially the same diameter as the interior of and slideable in 20 said cylinder and operatively associated with said saddle, a pump-cylinder, valve means for said pump-cylinder, a plunger slideable in said pump-cylinder to actuate said piston by liquid pumped by said plunger, means to 25 operate said plunger, a liquid-reservoir, and means to force liquid from said reservoir through said pump-cylinder valve means to obtain a quick initial lift of said saddle 30 through movement of said piston.

9. In a lifting-jack, the combination of a substantially-horizontal tubular-member one longitudinal portion of which forms a power-cylinder and another lengthwise section of which constitutes a liquid-reservoir cylinder, carrying-wheels for said tubular-member, a load-saddle, a power-piston slideable in said power-cylinder, means operatively connecting said power-piston and said load-saddle, a closure for one end of said tubular member, a pump-cylinder mounted inside of said reservoir-cylinder on said end closure and connected to said reservoir and to the said power-cylinder, a plunger reciprocatory in said pump-cylinder, means to operate said plunger to force liquid from said reservoir into said power-cylinder to slide said power-piston to raise said load-saddle, means to permit return of liquid from said power-cylinder into said reservoir, a reservoir-piston slideable in said reservoir-cylinder on the outside of said pump-cylinder and adapted to force liquid from said reservoir into said power-cylinder to obtain a quick initial lift of said load-saddle, and means to operate said reservoir-piston. 40

10. In a lifting-jack, the combination of a substantially-horizontal tubular-member, carrying-wheels for said tubular-member, a cross-wall inside of said tubular-member dividing it into a power-cylinder and a reservoir-cylinder, a load-saddle, a power-piston reciprocatory in said power-cylinder, means operatively connecting said power-piston and said load-saddle, a closure for one end of said tubular-member, a pump-cylinder inside of said reservoir-cylinder and mounted on said end closure, said division-wall being mounted on said pump-cylinder, valved conduits connecting said pump-cylinder with said reservoir and power cylinders, a plunger reciprocatory in said pump-cylinder to force liquid from said reservoir into said power-cylinder to actuate said power-piston to raise said load-saddle, means to permit return of liquid from said power-cylinder into said reservoir to allow descent of said load-saddle.

cylinder to actuate said power-piston to raise said load-saddle, means to operate said pump-plunger, means to permit return of liquid from said power-cylinder into said reservoir to allow descent of said load-saddle, a 70 reservoir-piston surrounding and slideable on said pump-cylinder in said reservoir-cylinder, and means to slide said reservoir-piston to force liquid from said reservoir into said pump-cylinder to obtain a quick initial lift 75 of said load-saddle.

11. In a lifting-jack, the combination of a main-cylinder, a movably-mounted load-saddle, a piston of substantially the same diameter as the interior of and slideable in 80 said cylinder and operatively associated with said saddle, a pump-cylinder, valve means for said pump-cylinder, a plunger slideable in said pump-cylinder to actuate said piston by liquid pumped by said plunger, means to 85 operate said plunger, a liquid-reservoir, and means to force liquid from said reservoir through said pump-cylinder valve means to obtain a quick initial lift of said saddle 90 through movement of said piston.

12. In a frameless lifting jack, the combination of a substantially-horizontal cylinder, front and rear carrying-wheels for the opposite end portions of said cylinder, said cylinder constituting the sole, main, supporting member between said front and rear carrying-wheels, a load-saddle, means mounting said load-saddle on said cylinder with capacity for elevation and descent of the saddle, a piston of substantially the same diameter as the interior of and slideable in said cylinder, means operatively associating said piston with said saddle mounting, and means to pump fluid in said cylinder and to permit its release to actuate said piston to raise and 100 lower said saddle.

13. In a frameless lifting jack, the combination of a substantially-horizontal tubular-member of substantially uniform diameter, one longitudinal portion of which comprises a power-cylinder and another longitudinal portion of which forms a liquid-reservoir, front and rear carrying-wheels for the opposite end portions of said tubular-member, the latter constituting the sole, main, supporting member between said front and rear carrying-wheels, a piston of substantially the same diameter as the interior of and slideable in said power-cylinder, a 110 load-saddle, means mounting said load-saddle on said cylinder with capacity for elevation and descent of the saddle, means operatively connecting said piston and saddle mounting, means to pump liquid from said reservoir into said power-cylinder to actuate said piston to raise said load-saddle, and means to permit flow of said liquid from said power-cylinder into said reservoir to allow return movement of said piston and the descent of said load-saddle. 115

120

125

130

14. In a frameless lifting-jack, the combination of a substantially-horizontal cylinder slotted along its top for a portion of its length, front and rear carrying-wheels for the opposite end portions of said cylinder, the latter constituting the sole, main, supporting member between said front and rear carrying-wheels, a bell-crank lever fulcrumed on said cylinder, a load-saddle mounted on said lever, the latter in the lowermost position of said saddle extending through said slot and being, at least in part, accommodated in said cylinder, a piston of substantially the same diameter as the interior of and slidable in said cylinder, means operatively associating said piston with said lever, means to pump fluid into said cylinder and to permit its release therefrom to actuate said piston to raise and to lower said saddle.
15. In a frameless lifting-jack, the combination of a substantially-horizontal tubular-member slotted along its top for a portion of its length, another longitudinal section of said member comprising a power-cylinder, and a third lengthwise portion of said member forming a liquid-reservoir, front and rear carrying-wheels for the opposite end portions of said tubular-member, the latter constituting the sole, main, supporting member of the jack between said front and rear carrying-wheels, a piston of substantially the same diameter as the interior of and slidable in said power-cylinder, a load-saddle, operating means extended through the slot of said tubular-member and operatively connecting said piston and load-saddle, means to pump liquid from said reservoir into said power-cylinder to actuate said piston to raise said load-saddle, and means to permit flow of said liquid from said power-cylinder into said reservoir to allow return movement of said piston and the descent of said load-saddle.
16. In a frameless lifting-jack, the combination of a main substantially-horizontal cylinder, front and rear carrying-wheels for the opposite end portions of said cylinder, the latter constituting the sole, main, supporting member of the jack between said front and rear carrying-wheels, a load-saddle, a piston of substantially the same diameter as the interior of and slidable in said cylinder, means operatively associating said piston with said saddle, a pump-cylinder demountably supported in said main cylinder, a plunger slidable in said pump-cylinder, valve means for said pump-cylinder, and means to operate said plunger to actuate said piston through the means of liquid pumped in said pump-cylinder.
17. In a frameless lifting-jack, the combination of a main substantially-horizontal cylinder, front and rear carrying-wheels for the opposite ends of said cylinder, the latter constituting the sole, main, supporting member

of the jack between said front and rear carrying-wheels, a piston of substantially the same diameter as the interior of and slidable in said cylinder, a load-saddle, means operatively associating said piston with said saddle, a pump-cylinder in said main cylinder, a plunger slidable in said pump-cylinder, valve means for said pump-cylinder, means to operate said plunger to actuate said piston through the means of liquid pumped in said pump-cylinder, and means supporting said pump-cylinder, plunger and plunger-operating means as a unit demountably in said main cylinder.

18. In a frameless lifting-jack, the combination of a substantially-horizontal cylinder with a slot through its top, front and rear carrying-wheels for the opposite end portions of said cylinder, said cylinder constituting the sole, main, supporting member between said front and rear carrying-wheels, a power-piston slidable in said cylinder, hydraulic means to slide said piston in said cylinder, a load-saddle, means rockingly mounting said saddle on the top of said cylinder and adapted to occupy said slot, means operatively connecting said piston and saddle mounting, and spring means housed in said cylinder in substantially horizontal relation in the lowermost position of said saddle and tending to hold the latter down and extending up through said slot in the uppermost position of said saddle.

19. In a frameless lifting-jack, the combination of a substantially-horizontal cylinder having a slot through its top, front and rear carrying-wheels for the opposite end portions of said cylinder, said cylinder constituting the sole, main, supporting member between said front and rear carrying-wheels, a bell-crank lever fulcrumed on said cylinder and having an arm projecting down through said slot, a load-saddle mounted on said lever, an anti-friction roller on said lever-arm, a power-piston slidable in said cylinder and bearing against said roller, and means to slide said piston to raise or to lower said lever and load-saddle.

In witness whereof I have hereunto set my hand.

IRA A. WEAVER.
